UNITED STATES PATENT OFFICE.

WILLIAM W. WALLACE, OF FRANKFORT, INDIANA.

TILE-TABLE.

SPECIFICATION forming part of Letters Patent No. 315,359, dated April 7, 1885.

Application filed December 1, 1884. (No model.)

To all whom it may concern:

Be it known that I, WILLIAM W. WALLACE, a resident of Frankfort, in the county of Clinton and State of Indiana, have invented certain new and useful Improvements in Tile-Tables, of which the following is a specification.

My invention relates to a tile-table for receiving and carrying a tile, which is received thereon in a stick and then cut into the requisite lengths by a traveling cutter.

One of the objects of my invention is to provide an endless tile chain or carrier which will receive the tile as it comes from the dies in a twisting or spiral movement without injuring or straining the web of the tile.

Various features of invention are requisite to carry out fully all the objects of my invention.

Another object of my invention consists in providing telescopic legs to support the frame and carrier, so that either end of the table can be easily and quickly adjusted to the desired height, all of which will be fully set forth in the description of the accompanying drawings, forming a part of this specification.

Figure 1 shows a side elevation of my invention; Fig. 2, an end elevation of one of the carrying-sections; Fig. 3, a side elevation of the same; Fig. 4, a top plan view; Fig. 5, a cross-section of the cutting-frame, showing the cutting device in elevation.

A represents two side sills or frame-pieces, connected together by suitable cross-girders, and supported upon posts or legs 18, and forming the frame-work of the table.

B represent drums journaled upon suitable shafts at either end and between the frame-pieces A, and adapted to be revolved by the endless chain working thereon. The endless chain is composed of two sets of links upon either side of the carrier-sections C. Each link is composed of two pivoted sections, 1 and 2, which operate together in the manner hereinafter explained. The link 1 is pivoted to the carrier-sections C by a journal or stud, 3. Link 2 is pivoted to link 1 by pivots 4 at either end of the sections 1 and 2.

c represent brackets or ears projecting up from the top surface of carrier-sections C.

D represents shafts journaled on gudgeons d, passing through the ears c.

E represents pulleys mounted upon shafts D.

F represents endless bands passing around the pulleys E, and adapted to move freely thereon under the action of the tile.

I prefer to place four pulleys, E, supporting two endless bands, F, upon each of the sections C for supporting the tile, leaving a space between these bands.

5 represents a bracket rigidly secured to one side of the section C.

6 represents an arm attached to the bracket 5 by means of the set-screw 7, so as to adjust the arm 6 at any desired angle to accommodate the size of tile.

8 represents a friction-roller journaled in the bifurcated ends of the bracket 6. This roller is preferably covered with felt or other substance which will prevent injury of the tile T, which is in frictional contact therewith.

In order that the sections C may be automatically brought into a horizontal position quickly as they pass the endless roller B at the front end of the machine, I connect the parts as follows:

9 represents a lug projecting out from the foot of the bracket 5 vertically over the hinge 4 of the sections 1 and 2. The links 1 and 2 are connected to the carrier C, so that their top edge is in contact with the lug 9. The forward end of link 2 is rounded off, as shown by dotted lines, Fig. 3. When link 2 is in an inclined or nearly vertical position passing around the drum B, the inclined or rounded edge strikes the lug 9, which forces it into the horizontal position and turns the carrier-sections C down to a horizontal position, ready to receive the tile before it arrives under the delivering-die of the tile-machine. This endless tile-carrier is especially adapted to receive and carry properly a section of tile delivered from the spiral or twisted auger. The endless belt will move under the twist of the ejecting-die, and will allow the tile to turn on said endless belts F, which have a tendency to carry the tile laterally to one side.

In order to prevent the tile from being carried off the endless belts F, I provide the guide frictional roller 8, journaling on the bracket-arm 6, which is adjusted to suit the different sizes of tile by the set-screw, as before explained. Thus a very long stick or length of tile may be properly laid onto the

endless belts F, the series of sections C carrying the stick or web of tile.

In order that the tile may be cut vertically across, it is necessary to have the knife or cutting devices travel along with the section and to perform the act of cutting while it progresses or travels with the tile. To accomplish this I have provided the following instrumentalities:

- 10 represents a tramway provided upon one side of the sills A.
- 11 represents a slide or bed piece of the cutting-frame, which is carried on said tramway automatically by one of the carrier-sections 15 1 and 2.
- 12 represents a bar hinged to slide 11, and carrying a bow, 13, and connecting-wire 14.
- e* represents the hinge-joint connecting hinge-bar 12 to slide 11.
- 15 represents a link pivoted in a slot cut in slide 11.
- 16 represents a lug projecting from arm 12, so as to strike against the link 15 when it is in a vertical position and raise it to clear the carrier-lug, as shown in Fig. 5. As the bow 13 and arm 12 are carried down toward the tile to make the cut to divide it into lengths, the lug 16 passes off the link 15, and it drops down and engages with the carrier-lug 17. This 30 lug 17 is attached to link 2 of the endless chain. Thus, when the wire 14 and bow 13 are revolved in the position shown in Fig. 5, the bed or sill 16 can be slid laterally back upon the tramway 10 to the desired position for cutting the tile at the proper length. When the bow 13 and wire 14 are carried down so as to allow link 15 to drop down to engage with the lug 17, the cutting devices are carried forward by the endless-chain link 2 and travel with the tile.
- 40 When traveling in this position, the tile is cut into the proper length, and the cutting device is raised up, as shown in Fig. 5, and slid back into position for a second forward movement for cutting an additional length of tile. The 45 endless belts F, which travel around the pulleys E, may be made of duck, leather, felt, or other suitable material. This device will receive tile as it is ejected from the die traveling in a spiral direction without twisting or injuring the section, which is received and carried by the endless-chain devices herein shown, and can be readily cut into requisite lengths.
- 55 One of the advantages derived from the use of my tile-carrier is that it will turn freely on the belts under the die motion without danger of being twisted off, and without the use of oil or water to lubricate the surface of the tile, which is not only expensive, but injures the material carried.
- 60 Another important feature of my invention is the automatic means for bringing the sections C into a horizontal from a vertical position instantly, so that the tile is always delivered upon the endless belts at the proper point, 65 preventing the tile from dropping or sagging,

which would otherwise occur with these sections brought into a horizontal position very gradually.

In order that the endless chain and the supporting-sills A may be adjusted to the right 70 height to the machine, I provide the following instrumentalities:

18 represents legs, which are made U-shaped, or with ribs *i* upon either side, as shown in Fig. 1.

75 20 represents the upper section of the telescopic legs, which is securely attached to the sill-pieces A; and 21 represents ears or grooves formed in projections, which serve as bearings for the ribs *i* working therein.

80 22 represents an ear projecting from the section 21.

85 23 represents a screw-shaft tapping through said ear, which journals loosely in the top flange of the standard 20.

24 and 25 represent bevel-gears.

90 26 represents a crank fitting on the shaft of bevel-gear 25, for turning the same and raising and lowering the section 20 through the medium of the screw-rod 23, raising and lowering the ears 21, which slide on the ears *i*, as before stated. This mode of adjusting the table to the tile-die is very important, as it prevents the dropping or sagging of the tile delivered on the endless bands F, and provides 95 readier means for adjusting these bands vertically as they shrink or swell under the atmospheric changes to which they are liable, and this is an important feature of my invention.

100 A modification in the mode of arranging the side guide-pulley, 8, in connection with the transverse endless bands on the carrier-section C, might be employed and allow the tile to turn.

105 Instead of guide-pulley 8, side guides might be attached to the bands themselves, which could be held stationary on their pulleys and yet hold the tile in position on the table and allow it to turn; but such devices would be 110 the equivalent of the clauses of claims wherein the adjustable guide-pulley 8 is not made a specific feature.

115 Having described my invention, what I claim is—

1. A tile-carrier composed, substantially, of traveling sections C, provided with supporting-pulleys E, and one or more transverse endless belts, F, for receiving the tile, substantially as specified.

120 2. In combination with the sections C, having the endless belts F, working on pulleys, the guiding-pulley 8, secured upon one side of the section, for preventing the tile being carried laterally off of the endless belts, substantially as specified.

125 3. The combination of the section C, having an attached laterally-projecting lug, 9, the links 1, pivoted to the said sections, and the links 2, pivoted to the ends of the links 1, and 130

- having a curved end to strike the lug on the | one upon the other and adjustable lengthwise, section C and turn it to a horizontal position, substantially as described.
4. The combination, with the endless chain, 5 of the tramway 10, the slide 11, moving thereon, the bar 12, hinged to the slide, the cutting-frame carried by the bar, and means, substantially as described, whereby the slide can be moved by the chain, substantially as described.
- 10 5. The combination, with the endless chain having the lug 17, of the tramway 10, the slide 11, moving thereon, the bar 12, hinged to the slide and having the attached lug 16, the cutting-frame carried by the bar, and the 15 swinging link pivoted to and extending across the slide, substantially as described.
6. The combination, in a tile-machine, of the side sills and the carrier traveling horizontally thereon, with a supporting-leg at each 20 end of the sills, composed of sections sliding
- one upon the other and adjustable lengthwise, for raising or lowering one or both ends of the sills with the carrier, substantially as described.
7. The combination of the side sills, A, the tile-carrier traveling thereon, a supporting-leg at each end of the sills, composed of two sections sliding one upon the other, and having the ears 20 and 21, the screw 23, engaging the ear 20, and the bevel gear-wheels 24 and 25, for raising and lowering one or both ends of the sills and carrier, substantially as described. 25 30

In testimony whereof I have hereunto set my hand.

WILLIAM W. WALLACE.
